UNITED STATES PATENT OFFICE.

ERNST LAUSCHKE, OF LAKE, ASSIGNOR TO ARTHUR M. AND ALSON E. BARNHART, OF CHICAGO, ILLINOIS.

DESIGN FOR A FONT OF PRINTING-TYPE.

SPECIFICATION forming part of Design No. 17,800, dated October 18, 1887.

Application filed May 31, 1887. Serial No. 239,911. Term of patent 14 years.

To all whom it may concern:

Be it known that I, ERNST LAUSCHKE, a subject of the Emperor of Germany, residing in the town of Lake, county of Cook, and State 5 of Illinois, have invented and produced a new and original Design for a Font of Printing-Type, of which the following is a specification, reference being had to the accompanying typographical illustration, forming a part hereof.

10 The general character of the design is semi-Gothic of medium weight; and it consists of capitals, figures, points, character &, dollar-mark, one center and one end ornament.

15 The general features are a combination of the Gothic with the style known as "Latin," the upper half of such letters as A, B, D, H, I, J, L, N, P, R, V, X, and Y being purely Gothic, while the lower half is Latin.

20 The special features are shown in capitals E and F, the center horizontal strokes which extend slightly beyond the upper line being sharpened or mitered on both sides at the end. In capital G the center line starts flush with the lower curved line, runs inward, bending 25 slightly down, and ends with a disk; capital H, the two strokes are wider apart at the bottom than at the top, the line connecting them running from near the middle of the left-hand line diagonally upward to near the top of the 30 right-hand line; capital M, the two outside

lines run upward, curve at the point of junction at the top, and a straight line extends from the center of junction inside downward a short distance. Capital W is the reverse of capital M, being an inverted capital M. Capital T has a bar across the top mitered at each end, while the rest of the letter is made by a curved line, the end of which is mitered. Capital U has one straight line on the right side and a curved line on the other. 35 40

I claim—

The design for a font of printing-type herein shown and described, having the upper half 45 of such letters as A, B, D, H, I, J, L, N, P, R, V, X, and Y strictly Gothic and the lower half Latin, and having the letters M and W of converging side lines joining a shorter middle line by short curves, letters E and F having their middle lines as long as the top lines, letter G having the center cross-line flush 50 with the curve at its outer end, terminating inwardly in a disk, and letter T having its top line mitered in the same direction at both ends and the remainder a curve of helical form, substantially as set forth.

ERNST LAUSCHKE.
